6 SHEETS—SHEET 3.

<img alt="A detailed technical cross-sectional diagram of a mechanical device, likely a pump or valve assembly. The diagram shows various components including a central vertical rod (60), a top cap (61), a main housing (62), and a base assembly (63). The base assembly includes a housing (64), a piston (65), a rod (66), a valve (67), and a seat (68). A side view of the base assembly is also shown, revealing internal parts like 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, UNITED STATES PATENT OFFICE.

LOUIS A. HAWTHORNE, OF NEWARK, AND BERTRAM S. PERO, OF JERSEY CITY, NEW JERSEY, ASSIGNORS TO STEEL UTILITIES, INCORPORATED, A CORPORATION OF NEW YORK.

METAL-WORKING MACHINE.

1,311,276.

Specification of Letters Patent. Patented July 29, 1919.

Application filed May 5, 1917. Serial No. 166,585.

To all whom it may concern:

Be it known that we, LOUIS A. HAWTHORNE and BERTRAM S. PERO, both citizens of the United States, residing at Newark, 5 New Jersey, and Jersey City, New Jersey, respectively, have invented certain new and useful Improvements in Metal-Working Machines, of which the following is a specification.

10 The invention relates to distance determining devices for relatively positioning metal shapes, beams and the like, with respect to tools, such as a punch or punches, for operating thereon, as in machines for 15 punching the rivet holes in structural shapes.

Objects and advantages of the invention will be set forth in part hereinafter, and in part will be obvious herefrom, the same being attained through the instrumentalities 20 and combinations pointed out in the appended claims.

The invention consists in the novel parts, constructions, arrangements, combinations and improvements herein shown and 25 described.

The accompanying drawings, referred to herein and forming a part hereof, illustrate one embodiment of the invention and together with the description serve to explain 30 the principles thereof.

Of the drawings:

Figure 1 is a fragmentary top plan of a distance determining device constructed in accordance with the principles of the invention; 35

Fig. 2 is a side elevation, looking at Fig. 1 from the foot of the sheet;

Fig. 3 is a fragmentary section, on an enlarged scale, of the upper right hand portion of Fig. 1, omitting the motor; 40

Fig. 4 is a similar fragmentary section, on an enlarged scale, of the upper left hand portion of Fig. 1, omitting the bevel gears and shafting;

Fig. 5 is a fragmentary section, substantially on the line A—B of Fig. 3; 45

Fig. 6 is an elevation, with parts broken away and parts in section, substantially on the line C—D of Fig. 1;

Fig. 7 is an elevation, of the distance determining device, looking thereat from the right in Figs. 1 and 2; and a punching mechanism co-operating therewith or controlled thereby; and 50

Fig. 8 is a diagram, showing parts of the

mechanism and the controlling circuits therefor.

Referring to the accompanying drawings, illustrating by way of example one embodiment and application of the invention, the 60 same is shown adapted to operate upon a structural shape in the form of an I-beam, the general arrangement of the punch traveling means and of the punch operating means being substantially the same as shown in application Serial No. 839,368 filed May 18, 1914, now Patent No. 1,241,257 dated Sept. 25, 1917. 65

The shape α (Fig. 7) is shown resting upon rollers 2, arranged in a series along 70 and beneath the shape, which rollers are driven either continuously or intermittently to propel or travel the shape endwise. In the illustrated embodiment, the mechanism is adapted to effect relative positioning of 75 the shape and punches transversely of, or across the shape, the punches and their dies traveling to and fro across the shape. The means for relatively positioning the shape and the punches in a longitudinal direction, 80 as shown, are of a different form wherein the shape travels relatively to the punches. The mechanism for so longitudinally positioning the shape comprises a traveling head 3 traveling on guideways 4 and 5, its movement and stopping being controlled 85 through a screw shaft 6. The head 3 has an extension 7 against which the forward end of the shape α abuts, and against which the shape presses under the impulsion of the 90 driven rollers 2, so that the head 3 may longitudinally position the shape relatively to the punches. This form of mechanism, as shown, is substantially that shown in application Serial No. 842,231 of L. A. Haw- 95 thorne, filed June 1, 1914, now Patent No. 1,241,258, dated Sept. 25, 1917.

The punches are shown as two in number, 8 and 9, and as having corresponding dies 10 and 11. The punches 8 and 9 are mounted in a transversely movable carrier 12, slidably mounted on guides on the punch structure, which carrier is in screw-threaded engagement with a screw shaft 13, the screw shaft being mounted in bearings 14 and 15 100 upon the punch structure. The dies 10 and 11 are mounted in a carrier 16, also slidably mounted on guides on the punch frame, which carrier is in screw-threaded engagement with a shaft 17, the shaft 17 being jour- 105

110

naled at 18 and 19 on the punch frame. The punches and dies, as shown, are operated to punch the shape substantially in the manner and by the mechanism described in said 5 co-pending application Ser. No. 839,368 of Wurts & Swinnbank, now Patent No. 1,241,257.

Suitable means are provided for rotating in unison the shafts 13 and 17, thereby to 10 travel the carriers 12 and 16 and therewith the punches and dies, across the machine to effect the desired relative positioning thereof transversely of the shape, so as to properly position the hole or holes with respect to 15 the width of the shape. The co-operative longitudinal positioning of the shape will be effected by the distance determining device already referred to and partially described.

In the embodied form of means for causing and controlling or determining the rotation in unison of the shafts 13 and 17, the shaft 13 is provided with a bevel gear 20 meshing with a beveled gear 21, the latter rotating with, but being slidably along, a shaft 22. 25 Shaft 22 is mounted in bearings 23, 24 and 25 upon the punch frame, and is held in longitudinal position by a collar 30 bearing on bracket 24. Shaft 17 has fixed to the end thereof a beveled gear 26, meshing with a 30 bevel gear 27, which is mounted upon the shaft 22 so as to be longitudinally slidable therealong similarly to the gear 21.

The distance determining device, as embodied, controls the positioning of the punch or punches with their corresponding dies by controlling and determining the rotation of the shaft 22. The distance determining device may be constructed or adjusted for any system of distance units. As embodied it 35 operates on the foot and inch system and is designed to be operated for inches and sixteenths-of-an-inch, and it is of sufficient scope to accommodate beams of the greatest width used in commercial practice. It will 40 be understood, of course, that the invention is applicable to other distance denominations and to other distance systems.

The shaft 22 has thereon a bevel gear 35 meshing with a bevel gear 36 upon a shaft 50 37, which shaft is journaled in bearings 38 and 39 in a supporting bracket 40. To the other end of shaft 37 is fixed a bevel gear 41, which gear meshes with a bevel gear 42 upon a shaft 43. Shaft 43 drives and controls in 55 unison shafts 13 and 17 and the rotation and stopping of shaft 43 is regulated and controlled by the settable distance determining devices, to determine through the mechanism just described the travel and positioning of 60 the punch or punches and dies.

In the embodied form of distance determining means, the settable devices are preferably automatically controlled by suitable means such as a perforated sheet α (Fig. 8), 65 co-operating with and controlling contacts 51

and 52 in electrical circuits, which are utilized to control the movement and position of mechanical devices co-operating with and acting upon the shaft 43.

In the embodied form of means for controlling the rotation of the shaft 43, a plurality of circularly arranged pins, sixteen in number, corresponding to the sixteenths-of-an-inch, are provided and in operation, an arm which rotates with shaft 43 is stopped by the pin corresponding to any desired sixteenth-of-an-inch, the pin being projected into the paths of the arm after the shaft 43 has made the requisite number of rotations corresponding to the desired number of inches of travel of the punch transversely to the beam. That is in embodied form, if the desired distance reading were four and seven-sixteenth inches, the arm rotating with the shaft 43 would sweep past each of the sixteen pins during the first inch, as none of these pins would be projected. The same thing would occur during the second inch and also during the third and fourth inches, but as the arm went about the next time on the next inch, the seven-sixteenth pin would be projected and the shaft 43 would be brought to rest after having imparted a travel of four and seven-sixteenths inches to the punch.

In the embodied form of mechanism, the shaft 43 has mounted thereon a gear wheel 56, which meshes with a pinion 57 on the shaft of a motor 58, the motor being mounted on the base 59 of the machine. The gear 56 is loose on shaft 43, having a friction drive comprising a spring 55 and friction disks 60. The shaft 43 has fixed thereon, to rotate therewith, an arm 61, which arm is held in angular position by suitable means, such as a spline 62. Arm 61, by reason of the connections between shaft 43 and the punch die blocks, has rotational travel proportionately to the relative travel of the punches and the shape and by stopping arm 61 in accordance with the successive readings of the distance record sheet, the punches and shape are successively positioned transversely for the various holes to be punched in the shape or like work.

The shaft 43 is journaled in a circular support 63 said support carrying the annular series of projectable and retractable pins 64 which determine the successive positioning or stopping points for the arm 61 for successive readings or positionings of the punch.

As embodied, the stop pins representing the sixteenth of-an-inch are solenoid operated. The pins 64 are reciprocably mounted in sockets in an apertured ring 65 the 125 ring extending outwardly from the support 63. The pins 64 are connected respectively to the cores 66 of a corresponding series of solenoids 67, which solenoids are supported or carried by the support 63.

- The various solenoid cores 66 are held de-centered, with their pins 64 retracted, by springs 68, acting between bushings 69 and nuts 70 on the heads of the respective cores.
- 5 The various solenoids are in circuit with the perforated distance record sheet, or other distance indicating or settable means, and with various parts of the mechanism, as will be later described.
- 10 Extending along shaft 43, and supported at one end by the support 63, and at the other end by a pillar or pedestal 71, is a bar 72. Said bar 72 is provided with a series of spaced teeth 73 representing inches of distance of travel of the punch. Meshing with the teeth 73 is the thread 78 on the exterior of a traveling circuit-closing device or circuit controller 79. Circuit controller 79 encircles shaft 43 to rotate therewith and to 15 travel therealong, due to the engagement of the teeth 78 with the teeth 73. The controller 79 is caused to turn with shaft 43 by suitable means such as a key 80. The lead of the thread 78 of controller 79 thus engages 20 a new tooth 73 for each rotation of shaft 43.
- 25 Mounted between each pair of teeth 73 is a spring-pressed circuit opening and closing device, said device as embodied comprising a contact head 81, which head is urged inwardly or toward the thread 78 by a spring 82. The device is held in position by a suitable bushing 83 screwed into the bar 72. Fixed to each contact head 81 is a pin 84, extending outwardly through the bushing 30 83. Each pin 84 carries at its external end an insulated circuit closing piece or head 85, which head when in the outward position is adapted to close the circuit between two spring contact fingers 86 and 87. The spring 35 contacts corresponding in the present case to inches, are mounted on insulating strips 76 and 77 carried on the bar 72. Thus as the shaft 43 rotates, the controller 79 will advance the distance of the pitch of its external 40 thread, that is, the distance of one tooth and the intervening space along the teeth 73, and the head of the thread 78, for each inch of advance or travel of the punch 8 across the shape 1, will close an additional circuit 45 contact 86 and 87 corresponding to the particular inch of travel.
- 50 Means are provided in the embodied form of the invention for successively closing the circuit for each sixteenth of an inch in each 55 of the successive inches. As embodied, there is supported on the pedestal 71, and preferably fixed to the journal bearing 90 of shaft 43 a circular disk 91, which disk is preferably radially apertured to receive a 60 series of projectable and selectable contact pins 92. Pins 92 are inwardly impelled, respectively, by springs 93 coiled thereabout, the device being held in its aperture by a screw bushing 94.
- 65 Each contact piece 92 has projecting rear-

wardly therefrom a pin 95 which pin has an insulated contact head 96. Each head 96 in its outwardly projected position is adapted to close the circuit between two spring contacts 97 and 98, which contacts are mounted

70 respectively on two insulating rings 99 and 100, mounted on the two faces of the disk 91. Fixed on the shaft 43, in alignment with the points of the contact pins 96, is a cam 101, and this cam, as the shaft rotates, successively raises the contact pins 92 and thus 75 successively closes the various circuits at the respective contact pieces 97 and 98.

Thus each sixteenth of an inch contact 96, 97 of the circular series just described is 80 closed in sequence during each inch, and the inch contacts are closed in sequence on the successive rotations of the shaft 43, through the consequent advance of the controller 79, the thread of which engages and pushes outwardly the successive contact pins 81.

The various solenoids 67 for the respective sixteenths-of-an-inch are in series connected with the inch contacts 86, 87 and with the sixteenth of-an-inch contacts, 97, 98, the 90 inch contacts being in parallel with each other and the various sixteenths-of-an-inch contact being in parallel with each other. Thus, the circuit will be made successively for each inch due to the advance of the controller 79, and the contact for each sixteenth-of-an-inch will be made successively in each inch due to the advance of the cam 101. The distance record sheet has, however, energized only one particular inch and only 95 one particular sixteenth-of-an-inch. Thus,

100 if the desired positioning of the punch in the punching machine is four inches and seven-sixteenths of-an-inch, the energized circuit will be closed at the seven sixteenths of-an-inch for each rotation of the cam 101, but during the first rotation of the shaft 43 the other series gap in the circuit which will be closed is for the first inch, which is not energized. The same will be true of the 105 second, third and fourth inches. When the controller 79 advances to project the contact closing device for the fifth inch, the circuit will be alive at this point, and when the seven sixteenths inch pin 92 is projected to 110 the circuit closing position by the cam 101, the circuit will be closed at both points, and the corresponding solenoid 67 will be energized, and the proper pin 64 projected into the path of the arm 61, and the punch will be 115 stopped at the desired position with respect to the beam, namely at the four and seven-sixteenths inch position.

120 Means are provided by the invention for slowing down the motor prior to the punch reaching the desired limit of travel, whereby the punch is slowed up preparatory to stopping. In the embodied form thereof, the mechanism is practically of the same form as that for controlling the inches of 125 130

travel, but in this case the contacts are arranged to vary the resistance in a certain manner so as to give the requisite decrease of speed to the motor. As embodied, a bar 120 is provided extending lengthwise of the shaft 43 at the opposite side thereof from the bar 72, the bar 120 having a series of teeth 121. The contacts may be similar in construction to the inch contacts already described, and detailed description thereof is unnecessary. The teeth 121 corresponding to the same inch value as particular teeth of the series 72 will be set ahead or to the right in Fig. 1 a sufficient distance to give the desired lead to the slow down device. Thus, if the motor slow down will coöperate five inches in advance of the corresponding stopping point, the teeth 121 will be placed four teeth on the lead to the right on the nut 79.

Referring more particularly to the diagram of Fig. 8 showing the various circuits and also certain parts of the machine which are shown in other figures of the drawing, 130 is a double pole contactor, connecting motor 58 for forward rotation. 131 is a double pole contactor, connecting motor 58, previously described for reverse rotation. 133 is a resistance, and 134, 135 and 136 are connections on resistance 133. 137 is an indicating lamp. 138 is a punch solenoid.

51, 52 is the keyboard or group of contacts coöperating with the distance record sheet *a*, as already described. The bottom 35 contacts of the keyboard are common and are connected to a thirty volt control line or circuit 174. 86, 87 is a group of stop contacts, one for each inch of punch travel as previously described. 141 is a group of 40 slow contacts, one for each inch of punch travel, likewise previously described.

The contact controller 79 coöperates with the foregoing as already described. 67 is the group of sixteen stop pins and solenoids 45 and 96, 97 is the group of sixteen contacts for timing the setting of the stop pins, both being previously described.

140 is a contactor which is operated on counter E. M. F. during acceleration of the 50 motor 58, and when closed it cuts out section 134—135 of the resistance 133. 142 is a contactor which when closed connects section 134—136 of the resistance 133, across the armature of the motor 58, for slow speed. 55 144 is a contactor which is energized when contactor 142 closes and contactor 146 is open. It makes a part of the circuit for indicating lamp 137. 145 is a contactor which when closed energizes the coil of 60 contactor 130. 146 is a contactor which when closed energizes the coil of contactor 131. 147 is a contactor which closes after the completion of any distance, as explained later, and which then 65 energizes the punch solenoid 138. 148 is a

contactor which is energized when the control or distance determining mechanism has returned to the zero position. Contactor 148 is energized by one side of its coil being connected to line 175 and the other side of its coil being connected to control line 174 through the closed zero contact of contacts 141. 149 is a contactor which, in its de-energized position, energizes the coil of contactor 145 and which in the energized position, energizes coil of contactor 147. 150 is a contactor which, in the de-energized position, energized coil of contactor 140, for high speed of motor 58, and in the energized position, energized coil of contactor 142 for slow speed of motor 58. 151 is a relay having a dash pot 177 for retardation in closing. 152 is a contactor energized from keyboard 51, 52 through key LT, for spacing less than an inch. 153 is a contactor energized when the proper inch contact of contacts 86, 87 is closed by contact controller 79. Contactor 153, when energized, connects one side of the 230 volt line 170 to solenoids 67. 154 is a group of sixteen contactors energized by contact S in keyboard 51, 52. When energized it connects one side of 230 volt line 170 to one side of the coil of stop pin solenoid 67, and also connects one side of the 30 volt line to one side of 95 contacts 96, 97. 155, 156 and 157 are three contactors which are energized through 0, 10 and 20 contacts of keyboard 51, 52. These contactors when energized, connect one side of the 30 volt line to the contacts of contactors 165, 166 and 167 respectively. 165, 166 and 167 are each groups of ten contactors. One of each group is energized by one of ten contacts I of keyboard 51, 52. 168 is a contactor, the coil of which is connected in 100 series with the coils of contactors 165, 166 and 167. It will close provided the "I" contact of keyboard 51, 52 is making contact. In the energized position, contactor 168 completes one side of the coil circuit of contactor 130. 161 is a limit switch, normally 105 closed, and operated by contact controller 79 to determine and regulate the extreme limit of travel of the punch. 230 is one side of 230 volt control circuit, and 171 is the other side thereof. 172 is one side of 172 volt power circuit, and 173 is the other side thereof. 174 is one side of the 30 volt control circuit, and 175 is the other side thereof. 176 is a resistance. 120

Description of operation.

Assume a reading of $4\frac{1}{16}$ inches, and the mechanism in zero position to start.

Through contact 0 on keyboard 51, 52, 125 one side of coil of contactor 155 is connected to line 174. The other side of coil of contactor 155 is connected to line 175, through contacts of contactor 148. This energizes contactor 155. 130

One side of the coils of contactors 165, 166 and 167 is connected to control line 174 through contact I of keyboard 51, 52. The other side of the coils is connected through 5 coil of contactor 168 and through contacts of contactor 148 to line 175. This closes contactor 168, which in closing connects resistance 176 in parallel with its own coil, allowing enough current to pass to close contactors 165, 166 and 167.

Contactor 155 being closed through its contacts it connects line 174 to the contacts of contactor 165. These contacts connect line 174 to the 4 inch contact of the series 15 of 86, 87 and 141.

One side of coil of contactor 145 is connected through the normally closed contacts of contactor 144, and through contacts of contactor 148 to line 175. The other side 20 of the coil of contactor 145 is connected through the normally closed contacts of contactor 149 and through contact W of keyboard 51, 52 to line 174. This closes contactor 145, which through its contacts connects line 170 to one side of the coil of contactor 130. The other side of the coil of contactor 130 is connected through the normally closed contacts of contactor 131, through limit switch 161 and through the 25 contacts of contactor 168 to line 171. This closes contactor 130, thereby connecting motor 58 as follows: through line 172 through the motor field, and through the contacts of contactor 130 to one side of motor 58, and 30 through line 173, through the contacts of contactor 130 to connection 135 of resistance 133. Thence through connection 134 of resistance 133 to the other side of motor 58 thereby causing motor to start.

40 The coil of contactor 140 is connected across the armature of motor 58 one side thereof going through the normally closed contacts of contactor 150. Contact 45 controller 140 closes at a pre-determined counter electro-motive force caused by motor 58, and in closing it short circuits section 134—135 of resistance 133, thereby connecting motor 58 directly across lines 172 and 173, for full speed forward.

50 As shaft 43 carrying arm 61 and contact closers or controllers 79 and 101 rotate, contact controller 79 is moved forward until the four inch contact of the contacts 141 is, in turn, closed, connecting line 174 through 55 the contacts of contactor 155 and through the contacts of contactor 165, to one side of the coil of contactor 150. The other side of the coil of contactor 150 is connected to line 175, thereby energizing contactor 150. Contact 60 controller 150 in so closing also acts to open one side of the coil of contactor 140, which inserts into the circuit of motor 58, section 134—135 of resistance 133.

Contactor 150 in closing, connects one 65 side of the coil of contactor 142 to one side

of motor 58. The other side of the coil of contactor 142 is connected to one side of the armature of motor 58. Contact 70 controller 142 in closing, connects section 134, 136 of resistance, as a shunt across the armature of motor 58, thereby causing slow speed of the motor. Contactor 142 in closing, also connects line 175 to one side of the coil of contactor 144, through the normally closed contact of contactor 144. The other side of 75 coil of contactor 144 is connected through the normally closed contact of contactor 146, through the normally closed contact of contactor 149, and through W contact on keyboard 51, 52 to line 174. This energizes contactor 144, which in closing, makes through its contacts a holding circuit for its coil from line 175.

Motor 58 now runs at slow speed, and continues to so run until contact controller 85 79 closes the contact 86, 87, which correspond to four inches. When this takes place, line 174 is connected to one side of the coil of contactor 153 and to one side of the coil of relay 151 through the contacts of contactor 155 and through the contacts of contactor 165. The other side of the coil of contactor 153 is connected to line 175 through the contacts of contactor 148, through contacts of contactor 154 and 90 through the selectively energized sixteenths of-an-inch contact 96, 97. When such selectively energized contact is closed by contact controller 101, contactor 154 has one side of its coil connected to line 175 through 95 the contacts of contactor 148 and the other side of its coil connected to line 174, through S contact of keyboard 51, 52. Therefore contactor 154 is energized. In closing contactor 154 connects line 170 to one side of 100 pin solenoid 67, which is the pin for the selected sixteenth of an inch.

Contactor 153 is energized when contact controller 101 closes the energized contact 96, 97. Contactor 153 in closing connects 110 line 171 to the common side or circuit branch of pin solenoids 67, thereby energizing and setting the pin solenoid selected by contactors 154. Contactor 153 in closing also makes a holding circuit for itself and relay 115 151. When arm 61 strikes the set pin 64 it stops, at the desired inch and sixteenth in accordance with the set or selected contacts 51—52.

Relay 151 has one side of its coil connected to line 174 through the four inch contact of contacts 86, 87, through contacts of contactor 165 and through contacts of contactor 155. The other side of the coil of relay 151 is connected to line 175, through the contacts 125 of contactor 145, the contacts of contactor 153 and through contacts of contactor 148. Therefore, relay 151 is energized and starts to close with dash-pot retardation. This retardation is long enough to allow arm 61 to 130

make at least one revolution. One revolution of arm 61, or a fraction thereof, thus takes place before the arm 61 strikes the selected stop pin, as already described. Relay 151 in closing connects line 174 through the W contact in keyboard 51, 52 to one side of the coil on contactor 149, and one side of the coil of contactor 147. The other side of the coil of contactor 149 is connected to line 175. Therefore, contactor 149 is energized, and when closed makes its own holding circuit, and deenergizes contactor 145, which in opening deenergizes contactor 130, and relay 151. Contactor 130 in opening deenergizes motor 58. One side of the coil of contactor 147 being connected to line 174 by the closing of relay 151, and the other side of said coil being connected to line 175, it energizes contactor 147, which through its contacts connects one side of punch solenoid 138 to line 171, and the other side of punch solenoid 138 is connected to line 170, and thereby operates the punch.

When the record sheet is advanced in the keyboard 51, 52, the circuit through 174-175 is broken, and all contactors released. After the record sheet reaches its new position, the circuit through 174-175 is again closed.

For a reading of "14 $\frac{1}{6}$ " inches, the operation is the same, except that contact 156 in keyboard 51, 52 is made instead of contact 155. This energizes contactor 156 and connects line 174 to the contacts of contactor 166, and so on to the "fourteen inch" contacts 86, 87 and 141.

If the following reading is greater than the last reading, contact HT in keyboard 51, 52 is used. If the reading is less, contactor 148 will remain in the deenergized position until contact controller 79 travels back and closes the zero contact 141. This is accomplished as follows: Line 175 connects through the normally closed contact of contactor 148, to one side of the coil of contactor 146. The other side of the coil of contactor 146 connects to line 174, thereby energizing contactor 146 which when closed connects line 171 to one side of the coil of contactor 131. The other side of the coil of contactor 131 is connected through the normally closed contacts of contactor 130 to line 171. This closes contactor 131, which connects motor 58 for reverse rotation.

Acceleration is effected in the same manner as forward rotation. Contactor 146 in closing also connects line 174 to RR contact of contacts 141. When contact controller 79 in returning closes contact RR, line 174, is connected through contact RR, of contacts 141 to one side of the coil of contactor 130 producing, as explained, slow speed of motor for forward rotation. After further reverse travel of contact controller 155, the contact of contacts 141 is closed, connecting line 174 to one side of the coil of contactor 148. The

other side of the coil of contactor 148 is connected to line 175 and contactor 148 is thus energized. Contactor 148 in closing makes connections for setting, as previously explained.

If the next setting is for a greater distance than the last setting, when line 174-175 has been closed, after the advance of the distance record sheet *a* in the keyboard 51, 52, line 174 is connected through contact HT of keyboard 51, 52 to one side of the coil of contactor 148, energizing this contactor the same as if contact controller 79 had returned to zero, and allowing the motor 58 to go forward at once.

There are provided, by certain features of the invention, means for detecting any failure in the operation of any of the foregoing mechanisms and parts, the embodied form of which is as follows:

Failure of contact S in keyboard 51, 52, Contactor 154 will not close. Inch contacts 86, 87 and 141 will be energized, and contact controller 79 will go forward, the motor 58 running first at high speed, and then slowing down, as previously explained; but when contact controller 79 leaves the energized contact 141, contactor 15 will be deenergized, which through its contacts deenergizes contactor 142. Contactor 144 as previously explained, is energized. One side of the coil of contactor 145 was connected to line 175, through the contacts of contactor 142 the contacts of contactor 144 and the contacts of contactor 148. Therefore, contactor 142 being deenergized, contactor 145 is also deenergized, which deenergizes contactor 130, disconnecting motor 58. Contactor 142 when deenergized connects line 175, through a normally closed contact, through a contact of contactor 144 to one side of the indicating lamp 137. The other side of lamp 137 is connected to line 174. Therefore, when the control goes from low speed to high speed, which indicates that the selected pin solenoid has failed to set, the motor 58 stops, and the indicating lamp glows, calling the operators' attention thereto.

Failure of I contact in keyboard 51, 52 prevents line 174 from being connected to contactor groups 165, 166, 167 and, therefore, contactor 168, which has its coil in series with the coils of contactors 165, 166, 167 cannot close. This prevents line 171 from being connected to the coil of contactor 130 and motor 58 will not start.

Failure of 155 or 156 contacts in keyboard 51, 52 prevents contacts 86, 87 from being energized, and therefore motor 58 will start and run until contact controller 79 operates the limit switch 161. The operation of this limit switch deenergizes contactor 130, thereby disconnecting motor 58.

The punch will operate only when relay 130

151 has functioned. The coil of relay 151 is energized on one side through the contacts of contactor 145, through the sixteenth-of-an-inch contacts, 96, 97 and through contacts of contactor 154. Therefore, if contactor 154 is not energized, corresponding to failure of S contact in keyboard 51, 52 relay 151 will not be energized.

If contact I on keyboard 51, 52 fails, contact groups 165, 166, 167 will not be energized, which, as explained prevents contactor 168 from closing, prevents motor 58 from starting, and, therefore prevents completion of the cycle up to the point of punching. In case of failure of 155, 156 contacts of keyboard 51, 52, none of the contacts 86, 87, 141 are energized, and consequently relay 151 cannot be energized, and the punch cannot operate.

20 What we claim as our invention and desire to secure by Letters Patent is:—

1. A machine for punching structural shapes including in combination means for longitudinally feeding the shape, means for 25 stopping the shape, punch and die blocks traveling together transversely to the shape, screw shafts on which the punch and die blocks are mounted, respectively, a shaft rotating proportionally to the relative travel 30 of the shape and punches, connections for rotating said last-mentioned shaft and said screw-threaded shafts together, an arm on said shaft and rotating therewith, an annular series of stop pins in the path of said 35 arm, a series of solenoids to project the stop pins as selected, circuit controlling devices comprising series of pairs of electrical contacts, a contact pin for each pair, each pair of contacts being closed by the correspond- 40 ing pin, a contact controller mounted upon and movable along said shaft and acting to close the corresponding contacts, a circular series of spring-pressed pins encircling said shaft, a corresponding series of pairs of 45 electrical contacts, a second contact controller mounted on said shaft to rotate therewith and to successively actuate the circularly arranged spring-pressed pins to close the corresponding pairs of contacts, 50 and circuit connections from the various contacts to the solenoids to energize a selected solenoid to actuate the corresponding stop pin to arrest the stop arm and the shaft.

2. A distance determining device for 55 metal punching machines including in combination a shaft rotating proportionally to the relative travel of the shape and punches, an arm on said shaft and rotating therewith, an annular series of stop pins in the path 60 of said arm, a series of solenoids to project the stop pins as selected, circuit controlling devices comprising series of pairs of electrical contacts, a contact pin for each pair, each pair of contacts being closed by the 65 corresponding pin, a contact controller

mounted upon and movable along said shaft and acting to close the corresponding contacts, circuit controlling means including a series of pairs of contacts encircling said shaft, a second contact controller rotating with said shaft and acting to close said encircling pairs of contacts, and circuit connections from the various contacts to the solenoids to energize a selected solenoid to actuate the corresponding stop pin to arrest the 70 stop arm and the shaft.

3. A distance determining device for metal punching machines including in combination a shaft rotating proportionally to the relative travel of the shape and punches, 80 an arm on said shaft and rotating therewith, a series of stop pins in the path of said arm, a series of solenoids to project the stop pins as selected, circuit controlling devices comprising series of pairs of electrical contacts, 85 a contact pin for each pair, each pair of contacts being closed by the corresponding pin, a contact controller mounted upon and movable along said shaft and acting to close the corresponding contacts, circuit controlling means including a series of pairs of contacts encircling said shaft, a second contact controller rotating with said shaft and acting to close said encircling pairs of contacts, and circuit connections from the various contacts to the solenoids to energize a selected solenoid to actuate the corresponding stop pin to arrest the stop arm and the shaft.

4. A machine for punching structural shapes including in combination means for longitudinally feeding the shape, means for stopping the shape, punch and die blocks traveling together transversely to the shape, screw shafts on which the punch and die blocks are mounted, respectively, a shaft rotating proportionally to the relative travel of the shape and punches, connections for rotating said last-mentioned shaft and said screw shafts together, an arm on said shaft and rotating therewith, an annular series of stop pins in the path of said arm, a series of solenoids to project the stop pins as selected, a plurality of coöperating circuit controlling devices comprising a longitudinally 100 disposed series of contacts along the shaft, a longitudinally traveling contact controller traveling along the shaft and coöperating therewith, a circular series of contacts about the shaft, a rotating contact controller rotating about the shaft and coöperating with the circular contacts, and circuit connections from the various contacts to the solenoids to energize a selected solenoid to actuate the corresponding stop pin to arrest the stop arm and the shaft.

5. A machine for punching structural shapes including in combination means for longitudinally feeding the shape, means for stopping the shape, punch and die blocks 110

traveling together transversely to the shape, means for moving and positioning the punch and die block relatively to the shape, said means including a rotating shaft, a plurality of cooperating circuit controlling devices comprising a longitudinally disposed series of contacts along the shaft, a longitudinally traveling contact controller traveling along the shaft and cooperating therewith, a circular series of contacts about the shaft, a rotating contact controller rotating about the shaft and cooperating with the circular contacts and circuit connections from the various contacts to the solenoids to energize a selected solenoid to actuate the corresponding stop pin to arrest the stop arm and the shaft.

6. A machine for punching structural shapes including in combination means for longitudinally feeding the shape, means for stopping the shape, punch and die blocks traveling together transversely to the shape, means for moving and positioning the punch and die block relatively to the shape, said means including a series of circuit controlling devices representing units in a distance denomination, a series of contacts representing sub-multiples of said distance denomination, means for successively closing the contacts of the first series to correspond to the relative travel of the punch and shape, and means for closing all the sub-multiple contacts between each succeeding closure of the contacts of the first mentioned series.

7. A machine for punching structural shapes including in combination means for longitudinally feeding the shape, means for stopping the shape, punch and die blocks traveling together transversely to the shape, means for moving and positioning the punch and die block relatively to the shape, said means including a series of circuit controlling devices representing units in a distance denomination, a series of contacts representing sub-multiples of said distance denomination, means for successively closing the contacts of the first series to correspond to the relative travel of the punch and shape and means for closing all the sub-multiple contacts between each succeeding closure of the contacts of the first mentioned series and a distance record sheet and cooperating means for selectively energizing the contacts corresponding to the successive distance readings.

8. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, a series of teeth extending alongside the shaft, a plurality of spring-pressed pins arranged between the

teeth, a corresponding series of pairs of electrical contacts, each pair of contacts being closed by the corresponding pin, a contact controller mounted upon and movable along said shaft and having on its exterior threads engaging with said series of teeth extending along the shaft, the thread successively engaging and actuating the stop pins of the series to close the corresponding contacts, circuit controlling means including a series of pairs of contacts encircling said shaft, a contact controller rotating with said shaft and acting to close said encircling pairs of contacts, and circuit connections from the various contacts to the solenoids to energize a selected solenoid to actuate the corresponding stop pin to arrest the stop arm and the shaft, the contacts along the shaft being in parallel, the contacts of the circular group being in parallel and the two groups being in series, a distance record sheet and cooperating means for selectively energizing the contacts corresponding to the successive distance readings.

9. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, circuit controlling devices comprising a series of pairs of electrical contacts, a contact pin for each pair, each pair of contacts being closed by the corresponding pin, a contact controller mounted upon and movable along said shaft and acting to close the corresponding contacts, a second circular series of spring-pressed pins encircling said shaft, a corresponding series of pairs of electrical contacts, a contact controller mounted on said shaft to rotate therewith and to successively actuate the circularly arranged spring-pressed pins to close the corresponding pairs of contacts, circuit connections from the various contacts to the solenoids to energize a selected solenoid to actuate the corresponding stop pin to arrest the stop arm and the shaft, a motor driving said shaft and a friction clutch between the motor and shaft, a distance record sheet and cooperating means for selectively energizing the contacts corresponding to successive distance readings.

10. A machine for punching structural shapes including in combination means for longitudinally feeding the shape, means for stopping the shape, punch and die blocks traveling together transversely to the shape, screw shafts on which the punch and die blocks are mounted, respectively, a shaft rotating proportionally to the relative travel of the shape and punches, connections for rotating said last mentioned shaft and said screw threaded shafts together, an arm on

said shaft and rotating therewith, an annular series of stop pins in the path of said arm, a series of solenoids to project the stop pins as selected, circuit controlling devices comprising series of pairs of electrical contacts, a contact pin for each pair of contacts, each pair of contacts being closed by the corresponding pin, a contact controller mounted upon and movable along said shaft 10 and acting to close the corresponding contacts, a circular series of spring-pressed pins encircling said shaft, a corresponding series of pairs of electrical contacts, a second contact controller mounted on said shaft to 15 rotate therewith and to successively actuate the circularly arranged spring-pressed pins to close the corresponding pairs of contacts, and circuit connections from the various contacts to the solenoids to energize a selected solenoid to actuate the corresponding stop pin to arrest the stop arm and the shaft, a distance record sheet and coöperating means for selectively energizing the contacts corresponding to successive distance readings.

11. A machine for punching structural shapes including in combination means for longitudinally feeding the shape, means for stopping the shape, punch and die blocks traveling together transversely to the shape, screw shafts on which the punch and die blocks are mounted, respectively, a shaft rotating proportionally to the relative travel of the shape and punches, connections for 30 rotating said last mentioned shaft and said screw threaded shafts together, an arm on said shaft and rotating therewith, an annular series of stop pins in the path of said arm, a series of solenoids to project the stop pins as selected, circuit controlling devices comprising series of pairs of electrical contacts, a contact pin for each pair, each pair of contacts being closed by the corresponding pin, a contact controller mounted upon and movable along said shaft and acting to close the corresponding contacts, a circular series of spring-pressed pins encircling said shaft, a corresponding series of pairs of electrical contacts, a contact controller mounted on said shaft to rotate therewith and to successively actuate the circularly arranged spring-pressed pins to close the corresponding pairs of contacts, circuit connections from the various contacts to the solenoids to energize a selected solenoid to actuate the corresponding stop pin to arrest the stop arm and the shaft, a distance record sheet, and coöperating means for selectively energizing the contacts corresponding to successive distance readings.

12. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, a series of teeth extending alongside the shaft, a plurality of spring-pressed pins arranged between the teeth, a corresponding series of pairs of electrical contacts, each pair of contacts being closed by the corresponding pin, a contact controller mounted upon and movable along said shaft and having on its exterior threads engaging with said series of teeth extending along the shaft, the threads successively engaging and actuating the stop pins of the series to close the corresponding contacts, a circular series of spring-pressed pins encircling said shaft, a corresponding series of pairs of electrical contacts, a contact controller mounted on said shaft to rotate therewith and to successively actuate the circularly arranged spring-pressed pins to close the corresponding pairs of contacts, and circuit connections from the various contacts to

13. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, a series of teeth extending alongside the shaft, a plurality of spring-pressed pins arranged between the teeth, a corresponding series of pairs of electrical contacts, each pair of contacts being closed by the corresponding pin, a contact controller mounted upon and movable along said shaft and having on its exterior threads engaging with said series of teeth extending along the shaft, the threads successively engaging and actuating the stop pins of the series to close the corresponding contacts, a circular series of spring-pressed pins encircling said shaft, a corresponding series of pairs of electrical contacts, a contact controller mounted on said shaft to rotate therewith and to successively actuate the circularly arranged spring-pressed pins to close the corresponding pairs of contacts, and circuit connections from the various contacts to

- the solenoids to energize a selected solenoid to actuate a corresponding stop pin to arrest the stop arm and the shaft, a distance record sheet and coöperating means for selectively energizing the contacts corresponding to successive distance readings.
14. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, a series of teeth extending alongside the shaft, a plurality of spring-pressed pins arranged between the gear teeth, a corresponding series of pairs of electrical contacts, each pair of contacts being closed by the corresponding pin, a contact controller mounted upon and movable along said shaft and having on its exterior threads engaging with said series of teeth extending along the shaft, the thread successively engaging and actuating the spring-pressed pins of the series to close the corresponding contacts, a circular series of spring-pressed pins encircling said shaft, a corresponding series of pairs of electrical contacts, a contact controller mounted on said shaft to rotate therewith and to successively actuate the circularly arranged spring-pressed pins to close the corresponding pairs of contacts, and circuit connections from the various contacts to the solenoids to energize a selected solenoid to actuate the corresponding stop pin to arrest the stop arm and the shaft, the contacts along the shaft being in parallel, the contacts of the circular group being in parallel and the two groups being in series, a distance record sheet and coöperating means for selectively energizing the contacts corresponding to successive distance readings.
15. A distance determining device for metal punching machines including in combination a shaft rotating proportionally to the relative travel of the shape and punches, an arm on said shaft and rotating therewith, an annular series of stop pins in the path of said arm, a series of solenoids to project the stop pins as selected, a series of teeth extending alongside the shaft, a plurality of spring-pressed pins arranged between the gear teeth, a corresponding series of pairs of electrical contacts, each pair of contacts being closed by the corresponding pin, a contact controller mounted upon and movable along said shaft and having on its exterior threads engaging with said series of teeth extending along the shaft, the thread successively engaging and actuating the spring-pressed pins of the series to close the corresponding contacts, a circular series of spring-pressed pins encircling said shaft, a corresponding series of pairs of electrical contacts, each pair of contacts being closed by the corresponding pin, a contact controller mounted on said shaft to rotate therewith and to successively actuate the circularly arranged spring-pressed pins to close the corresponding pairs of contacts, and circuit connections from the various contacts to the solenoids to energize a selected solenoid to actuate the corresponding stop pin to arrest the stop arm and the shaft, the contacts along the shaft being in parallel, the contacts of the circular group being in parallel and the two groups being in series, a distance record sheet and coöperating means for selectively energizing the contacts corresponding to successive distance readings.

- tact controller mounted on said shaft to rotate therewith and to successively actuate the circularly arranged spring-pressed pins to close the corresponding pairs of contacts, circuit connections from the various contacts to the solenoids to energize a selected solenoid to actuate the corresponding stop pin, to arrest the stop arm and the shaft, a motor driving said shaft and a friction clutch between the motor and shaft, a distance record sheet and coöperating means for selectively energizing the contacts corresponding to successive distance readings.
16. A machine for punching structural shapes including in combination means for longitudinally feeding the shape, means for stopping the shape, a punch and its die traveling together transversely to the shape, means for transversely traveling and positioning the punch and die including a distance record sheet and a coöperating series of electrical contacts and a distance determining device governed thereby.
17. A machine for punching structural shapes including in combination means for longitudinally feeding the shape, means for stopping the shape, a punch and its die traveling together transversely to the shape, means for transversely traveling and positioning the punch and die including a member representing distance units and a coöperating member representing sub-multiples of such distance units, and a distance record sheet controlling said members.
18. A machine for punching structural shapes including in combination punch and die blocks traveling together transversely to the shape, means for moving and positioning the punch and die blocks relatively to the shape, said means including a rotating shaft, a plurality of coöperating circuit controlling devices comprising a longitudinally disposed series of contacts along the shaft, a longitudinally traveling contact controller traveling along the shaft and coöperating therewith, a circular series of contacts about the shaft, a rotating contact controller rotating about the shaft and coöperating with the circular contacts and circuit connections from the various contacts to the solenoids to energize a selected solenoid to actuate the corresponding stop pin to arrest the stop arm and the shaft.
19. A machine for punching structural shapes including in combination punch and die blocks traveling together transversely to the shape, means for moving and positioning the punch and die blocks relatively to the shape, said means including a series of circuit controlling devices representing units in a distance denomination, a series of contacts representing sub-multiples of said distance denomination, means for successively closing the contacts of the first series to correspond to the relative travel of the

punch and shape, and means for closing all the sub-multiple contacts between each succeeding closure of the contacts of the first mentioned series.

5 20. A machine for punching structural shapes including in combination punch and die blocks traveling together transversely to the shape, means for moving and positioning the punch and die blocks relatively to the shape, said means including a series of circuit controlling devices representing units in a distance denomination, a series of contacts representing sub-multiples of said distance denomination, means for successively closing the contacts of the first series to correspond to the relative travel of the punch and shape and means for closing all the sub-multiple contacts between each succeeding closure of the contact of the first mentioned 10 series and a distance record sheet and coöperating means for selectively energizing the contacts corresponding to the successive distance readings.

21. A machine for punching structural shapes including in combination a punch, devices for effecting measured relative movement between the punch and work including a series of circuit controlling devices representing units of a distance denomination, a series of contacts representing sub-multiples of such distance denomination, means for successively closing the contacts of the first series to correspond to the relative travel of the punch and the work, and means for closing all the sub-multiple contacts between each succeeding closure of the contacts of the first-mentioned series.

22. A machine for punching structural shapes including in combination a punch, devices for effecting measured relative movement between the punch and work including a series of circuit controlling devices representing units of a distance denomination, a series of contacts representing sub-multiples of such distance denomination, means for successively closing the contacts of the first series to correspond to the relative travel of the punch and the work, means for closing all the sub-multiple contacts between each succeeding closure of the contacts of the first-mentioned series, and means for stopping the relative movement of the punch and work controlled from said contacts.

23. A machine for punching structural shapes including in combination a punch, 55 and a device for relatively positioning the punch and work, including a shaft rotating proportionately to the relative travel of the punch and work, a threaded member rotating with the shaft, teeth engaging the threaded member to move it along the shaft, a circuit and a plurality of circuit closing means arranged along the shaft and operated by said member, and means controlled by the circuit for stopping the relative 60 movement of the punch and work.

24. A machine for punching structural shapes including in combination a punch, and a device for relatively positioning the punch and work, including a shaft rotating 70 proportionately to the relative travel of the punch and work, a threaded member rotating with the shaft, teeth engaging the threaded member to move it along the shaft, a circuit and a plurality of circuit closing 75 means arranged along the shaft and operated by said member, and means controlled by the circuit for stopping the relative movement of the punch and work, a series of sub-multiples connected with said circuit 80 and closed in succession between the successive closings of said first-mentioned contacts.

25. A machine for punching structural shapes including in combination a punch, 85 and means for relatively positioning the punch and work including a shaft rotating, and a circuit closer traveling along the shaft, proportionately to the relative travel of the work and punch, a series of contacts representing distance denominations and arranged along the shaft to coöperate with said circuit closer, a series of contacts representing sub-multiples of said distance 90 denomination arranged about said shaft, and means for closing all said sub-multiple contacts in succession on each revolution of the shaft.

In testimony whereof, we have signed our names to this specification, in the presence 100 of two subscribing witnesses.

LOUIS A. HAWTHORNE.
